(57) **CLAIM**

The ornamental design for a holster as shown and described.

DESCRIPTION

FIG. 1 is a front perspective view of a holster of the present design;

FIG. 2 is a front elevation view of the holster of FIG. 1;

FIG. 3 is a rear elevation view of the holster of FIG. 1;

FIG. 4 is a left side view of the holster of FIG. 1;

FIG. 5 is a right side view of the holster of FIG. 1;

FIG. 6 is a top plan view of the holster of FIG. 1;

FIG. 7 is a bottom plan view of the holster of FIG. 1;

FIG. 8 is a cross-sectional view of the holster of FIG. 1 taken in the plane of and the direction indicated by line 8-8 of FIG. 6;

FIG. 9 is a cross-sectional view of the holster of FIG. 1 taken in the plane of and the direction indicated by line 9-9 of FIG. 6;

FIG. 10 is a cross-sectional view of the holster of FIG. 1 taken in the plane of and the direction indicated by line 10-10 of FIG. 6;

FIG. 11 is a cross-sectional view of the holster of FIG. 1 taken in the plane of and the direction indicated by line 11-11 of FIG. 6;

FIG. 12 is a cross-sectional view of the holster of FIG. 1 taken in the plane of and the direction indicated by line 12-12 of FIG. 2; and,

FIG. 13 is a cross-sectional view of the holster of FIG. 1 taken in the plane of and the direction indicated by line 13-13 of FIG. 2.

The broken lines in the drawings are for the purpose of illustrating portions of the holster that form no part of the claimed design. Surfaces forming part of the claimed design

(Continued)

are defined by shaded surfaces; broken lines immediately adjacent shaded surfaces represent boundaries of the claim and form no part thereof.
